UNITED STATES PATENT OFFICE.

ROBERT E. YOLTON, OF BIRMINGHAM, ALABAMA, ASSIGNOR TO KILBY FROG & SWITCH COMPANY, OF BIRMINGHAM, ALABAMA, A CORPORATION OF ALABAMA.

TONGUE-SWITCH STRUCTURE.

1,269,771.

Specification of Letters Patent. Patented June 18, 1918.

Application filed February 25, 1918. Serial No. 219,165.

To all whom it may concern:

Be it known that I, ROBERT E. YOLTON, a citizen of the United States of America, residing at Birmingham, in the county of Jefferson and State of Alabama, have invented certain new and useful Improvements in Tongue-Switch Structures, of which the following is a specification.

My invention relates to new and useful improvements in tongue switches and is designed to provide a novel mechanism for locking the heel of the switch tongues so as to hold the same securely in place in tongue switch bodies, yet which is so designed that the tongue may be easily removed, if desired, from the switch body.

More particularly, the objects of my invention are to provide a tongue holding means which will prevent the tongue from jumping up as the cars pass over the switch; which will prevent the tongue from moving forward under the traffic; which will permit the tongue to be easily tightened or loosened as may become necessary from time to time; which is adapted to permit the ready removal of the tongue from the switch body; and which is simple in its structure, readily assembled and so designed that liability of failure of any of its parts in service is minimized.

My invention further comprises the novel features of construction and arrangements of parts which in their preferred embodiments only are illustrated in the accompanying drawings which form a part of this specification, and in which:

Figure 1 is a plan view of the switch tongue body with the switch tongue in place.

Fig. 2 is a sectional view enlarged taken on the line A—A of Fig. 1.

Fig. 3 is a longitudinal sectional view enlarged taken on the line B—B of Fig. 1.

Fig. 4 is a detail view in side elevation of the heel end of the switch tongue.

Fig. 5 is a view corresponding to Fig. 2 of a modification of the tongue holding device as applied to tongue switches less than six inches in height.

Fig. 6 is a detail perspective view of the locking wedge shown in Fig. 2.

Fig. 7 is a detail perspective view of the locking bar.

Fig. 8 is a plan view corresponding to Fig.

1 with the switch body shown in Fig. 5 with the switch tongue removed.

Fig. 9 is a detail perspective view of the locking wedge shown in Fig. 5.

Fig. 10 is a sectional view taken on the line C—C of Fig. 4.

Similar reference numerals refer to similar parts throughout the drawings.

As illustrated in Figs. 1 to 4, the switch tongue body 1 is cast with a cavity 2 therein disposed below the seat 3 for the heel 4 of the switch tongue 5. The heel end of the tongue 65 is provided along its bottom surface with a lateral flange 6 which is curved to give the heel a substantially semicircular construction in plan, this flange being extended beyond the heel portion forwardly along the 70 tongue on each side to form bearing flanges 7 which gradually diminish in width toward the point of the tongue and disappear about midway of the tongue. The object of this arrangement is to substantially increase the 75 bearing surface of the tongue throughout its rear end and especially at its heel. The curved rear end of the flange 6 merges into the curved end wall 8 of the switch tongue proper, as will be more clearly seen in Fig. 80 4. The body is provided with the usual guard walls 9 and 10 and with the tread surfaces 11 and 12, the latter of which align with the switch tongue 5 and has its forward edge 13 curved to conform to the curvature 85 of the rear end of the tongue heel. The base level of the flange ways 14 and 15 on each side of the tread 12 are raised above the level of the tongue seat 3 approximately the thickness of the tongue flange 6 so that the 90 top surface of the latter lies flush with the flange ways. The tongue heel seat 3 is provided with a rectangular elongated slot 16 which extends from near the tread 12 along the center line of the switch body and opens 95 downwardly into the cavity 2. On the bottom face of the switch tongue heel, approximately in the center thereof, is a downwardly and forwardly inclined horn 17 having its rear face 18 convex and its front 100 corner edges rounded at 19. The slope of this horn and the length of the slot 16 are such that the horn will enter the cavity 2 and extend nearly to the bottom of the same. The cavity is inclosed on its front side by 105 an oblique vertical web 20 which joins the

top surface of the tongue supporting body portion at a point substantially forward of the front end of the slot 3, thus leaving at that point an overhanging lip 21, see Fig. 3.

5 A malleable locking wedge 22 is placed in the cavity 2 in the switch body, being inserted through a box 23 which has a bottom opening 24 entering the upper portion of the cavity 2. This locking wedge is provided with a downwardly and forwardly sloping rear face 25 corresponding to the slope of the forward face of the horn 17 which it engages. The front face 26 of the wedge lies in a vertical plane which is oblique to the longitudinal center line of the edge so that it will seat against the oblique web 20. At the rear end of the shank portion 27 of the wedge is a head 28 carrying a depending pin 29 which is adapted to engage in the hole 30 at the inner end of the locking bar 31 which extends from the cavity 2 through the opening 24 and rests upon the floor of the box 23 with its outer end disposed near the outer wall of the box 25 and upturned and slotted at 32 so that a bronze pin 33 may be dropped into this slot. A coil spring 34 is placed on this pin with one end resting against a bronze nut 35 which is screwed onto the threaded end of 30 the pin. This end of the pin beyond its threaded portion is reduced and provided with a square bearing end 36 adapted to be inserted in a square hole 37 in the inner wall of the box 23. The outer rounded end 35 of the pin can be inserted far enough into a hole 38 on the outer box wall to allow its squared end 36 to be fitted into the hole 37. When the pin has been thus placed in position crosswise of the box and through the 40 slot 32 its coil spring 34 will engage the locking bar 31 and force the latter transversely of the switch body toward the box 23 and in doing so will draw the wedge along the oblique web 20 which shifts it rearwardly against the horn 17 which being overhung by the sloping rear face 26 serves to hold the tongue firmly to the body.

For tongue switches of less height than six inches the same general mechanism is used except that the spring is designed to push against the locking wedge instead of pulling against it. This makes it necessary that the web 39 (Fig. 8) corresponding to the web 20 (Fig. 1), shall have a reverse 50 angular disposition and to correspond with this the malleable locking wedge 40 will have its vertical front face 41 disposed at an angle corresponding to that of the web 39. This wedge block has its rear face 42 similar to the sloping face 25 of the wedge 22. In view of the fact that the cavity 2 in the smaller switch body is shallower than in the larger switch body, the shank 43 of the locking wedge 40 preferably is disposed 55 near its bottom and has the pin 44 upturned

and adapted to be inserted in the hole 30 of a locking bar 45, similar to the bar 31 except that it is shorter. This bar has a bifurcated upturned end which receives the pin 33 which in this case is reversed to bring its squared end 36 into position to enter a hole 37 in the outer wall of the box 23 while its rounded end is inserted in the deeper hole 38 in the inner wall of the box. The coil spring 34, interposed between the locking 70 rod and the nut 35, acts to force the wedge 40 toward the horn 17 of the switch tongue, in doing which the wedge works against the oblique web 39 and is shifted rearwardly thereby to force the switch tongue against 75 its rear bearing face 13 in the body while holding the tongue down by the overhanging engagement of its sloping face 42 with the horn.

In assembling the switch using the holding device shown in Figs. 1 to 3, the locking wedge 22 is placed in the cavity 2 in the tongue switch body and the horizontal end of the locking bar 31 is inserted through the hole 24. The pin 29 of the locking 80 wedge is inserted through the hole 30 of the locking bar which is pushed inwardly to force the locking wedge far enough back into the cavity 2 to allow the tongue horn 17 to be dropped into place, after which an outward pull on the locking bar will cause the wedge to engage the horn 17. The pin 33 with the coil spring thereon is mounted with the spring engaging and pressing the bar outwardly and by turning the nut 35 so as 85 to compress the spring, the locking bar will be moved outwardly to tighten the malleable wedge against the horn of the tongue. Inasmuch as the malleable wedge is tapered in two directions and the tongue horn is set 90 at an angle where the wedge engages it and works between it and the web, the resultant action is to force the tongue both backwardly and downwardly, the degree of tightness of the tongue being regulated by 95 the compression of the spring. In assembling the device illustrated in Fig. 5 the switch tongue is first placed in position and the malleable wedge is then inserted through the inner wall of the box 23 and the 100 pin is inserted in reverse position to that above described with its spring acting to force the locking bar inwardly. To remove the switch tongue it is only necessary to loosen the nut 35 and shift the pin 33 into 105 the hole 38 until its squared end 36 clears the hole 37 and then remove the pin and spring, after which the wedge can be shifted to clear the switch tongue horn which leaves the tongue free to be removed from 110 the switch body. If desired a cotter key 46 may be inserted through the top of the yoke to close the top of the slot 32 in the bar 45 to prevent the latter dropping out of engagement with the pin 33.

This invention is not intended to be restricted in scope to the specific embodiment shown, but contemplates such modifications as come within the spirit and scope of the 5 claims.

Having thus described my invention, what I claim as new and desire to secure by Letters Patent, is:—

1. In a tongue switch structure, a body 10 having a rear end bearing seat for the switch tongue having a slot therein, a locking chamber below said seat, a spring box opening into said chamber, a switch tongue having a depending forwardly inclined 15 tongue adapted to project through said seat into said chamber, a transversely oblique front wall for said chamber, a locking wedge having a straight, downwardly facing rear wedging surface and a transversely oblique 20 front wedging surface, said surfaces respectively adapted to engage the tongue horn and the oblique front wall of said chamber, a locking rod loosely connected to the locking wedge and projecting through said 25 opening into said spring box and having its end upturned and slotted, a guide pin removably seated in said switch box and in the slotted end of the lock rod, and spring

means adjustable on said pin for urging said lock rod and locking wedge into operating position, substantially as described. 30

2. The combination with a switch tongue body having a slotted seat and a box at one side which has an opening therefrom to the space below said seat, a switch tongue having a rounded rear end mounted in said seat and having a depending horn adapted to project through said seat slot, a transversely movable locking wedge adapted to co-act with the switch body and tongue horn to 40 force the horn rearwardly and downwardly, an operating rod connected to the wedge and movable in said box and having its outer end upturned and slotted, a pin adapted to be inserted in said slot, means to removably seat said pin in the side walls of 45 said box, a coil spring surrounding the pin and engaging said upturned end of the lock bar at one end, and an adjustable spring seat on the pin engaging the other end of the spring, substantially as described. 50

In testimony whereof I affix my signature.

ROBERT E. YOLTON.
